UNITED STATES PATENT OFFICE.

HARRIETTE ENSLEY HODGSON, OF NEW YORK, N. Y.

ICE-RESCUE DEVICE.

Application filed March 2, 1926. Serial No. 91,662.

The purpose of this invention is to provide a simple and effective means for rescuing persons who have fallen through the ice. Many sad accidents occur every skating season, because, though there may be those at hand to help, there is no readily available and suitable instrumentality for effecting rescue. The subject of the invention is a large-diameter wheel or frame of adequate strength but light enough to be quickly rolled, slid or carried to the break in the ice, the frame being adapted to bridge the break and affording a central manhole through which the person in the water can 10 clamber or in which he may support himself. The frame is likewise provided at various points with cables, which can be held by rescuers at a distance from the hole so as to relieve the strain upon the weak 20 ice or to support and draw to safety the imperiled person in case the ice around the frame should break through, one or more of the cables being provided with a missile so that the ends of these cables can be thrown 25 to a considerable distance or to the bank of the pond or stream if necessary. In some instances the frame may be provided with folding extension members to increase the spread of the device over the ice.

30 In the accompanying drawings forming a part hereof;

Fig. 1 is a plan view of one form of the invention, one of the cables being shown coiled up and lightly tied to the frame, while 35 the others are shown extended and broken away, the end of one of the cables carrying a missile being seen;

Fig. 2 is a central cross-section through this form of the invention;

40 Fig. 3 is a plan view of another form;

Fig. 4 is a view of this form, partly in edge elevation and partly in cross-section;

Fig. 5 is a plan view of still another form having folded extension pieces, the folded 45 positions of these pieces being shown in broken lines and the extended positions in full lines, the intermediate portion of the members in this position being broken out for economy of space;

50 Fig. 6 is an edge elevation of Fig. 5, with the extension members folded; and

Fig. 7 is a cross-section through Fig. 6.

The device of Figs. 1 and 2 comprises an outer ring 2 of large diameter, an inner ring 55 3 of manhole size, and an openwork 4 connecting the rings. The rings 2 and 3 are

comparatively light and strong, and may be made with advantage of aluminum tubing, for example, though other suitable materials and forms may be employed. The 60 frame has a wide spread, so as to be effective in bridging breaks and holes in the ice, and may be made in different sizes ranging from about six feet to about nine feet, more or less. Where the device is to be kept in a boat-house or the like, its diameter should be such as to pass through the doorway of such a structure. The light but strong open-work 4, of tension elements, connecting the inner and outer rings may be made of a sufficiently stout wire mesh or of wires arranged like the spokes of a wire wheel, or they may even be of materials other than wire, the elements of the openwork being united to the rings by welding, soldering, or by appropriate mechanical connections.

At intervals about its circuit, the outer ring is provided with suitable attachments 5 for the connection of lengths of light, strong rope or wire cable 6, these cables 80 being long enough to extend to a considerable distance from the frame or even one or more of them to a fairly distant shore. For such purpose one or more of the cables may be provided at its end with a suitable 85 weight 7. When not in use, the cables will be suitably coiled and lashed to the frame or its openwork by light lacings or ties.

In case of an accident the frame can be quickly carried, rolled or dragged to the 90 opening in the ice, where the manhole ring 3 will be placed over the head of the person in the water, the ring 2 resting on the ice. The cable 6 can be quickly uncoiled and held by a number of rescuers standing at different 95 sides some distance back from the hole. In

special emergency, the ends of one or more of the cables may be thrown to greater distances. Also, one or more of the cables may be unashed at the bank and their ends be 100 left to trail or in the hands of rear guard rescuers while the frame itself is rushed out to the danger-point. Arrived at the hole, the frame may be immediately placed over the head and shoulders of the person in the water, or if the break is a large one, certain 105 of the cables may be uncoiled and thrown to persons at the opposite sides of the break, so that the frame can be pushed and pulled over the open water and if need be sup-

ported partly or entirely by those holding the ropes at opposite sides of the hole. The 110

person in the water climbs through the man-hole ring and crawls over the bridge afforded by the frame to safety. If he should be unable to do this, he may simply pass his head and arms through the central ring, and while thus clinging be drawn to solid ice by the rescuers at one side of the opening pulling in on the cables while those at the opposite side pay out the cables which they are holding.

As an additional advantage the frame may be provided with sufficient buoyancy so that it will not tend to sink in water in case the break in the ice should become badly enlarged. This can, of course, be accomplished by utilizing wood as a material for the frame or by means of floats suitably arranged so as not greatly to increase the bulk of the rescue device. The simplest float arrangement would be one as illustrated in Figs. 3 and 4, in which the rings 2^a and 3^a would be hollow and sufficiently large in cross-section to enclose buoyancy chambers 8 and 9. The buoyancy thus provided may be sufficient not only to support the device itself in the water, but even also to support or partially support the weight of a person.

The circular form of the frame and its rings is deemed preferable, but if desired the frame may be of other forms and Figs. 5 to 7 illustrate square frames 2^b and 3^b connected by openwork 4^b.

In order to increase the span of the device, extension members or arms 10 may be riv-

eted at 11 at the four corners of the outer frame so as either to fold compactly against the outer sides of this frame or to be extended upward therefrom. Naturally, it will be understood that the application of suitable folding extension members is not limited to a square or rectangular form of frame, but may be used in connection with any of the frames.

Various other changes and modifications will suggest themselves to the skilled mechanician.

What I claim as new is:

1. An appliance to save persons who have fallen through the ice, comprising a strong, portable, open frame of substantially equal large diameter in two dimensions adapted to be placed as a bridging support over a hole in the ice and affording a central manhole through which the person may escape, and cables attached to various portions of the frame to be held by persons on the ice or shore.

2. An appliance to save persons who have fallen through the ice, comprising a strong, portable, open frame of substantially equal large diameter in two dimensions adapted to be placed as a bridging support over a hole in the ice and affording a central manhole through which the person may escape, and a cable attached to the frame and provided with a missile.

HARRIETTE ENSLEY HODGSON.
